UNITED STATES PATENT OFFICE.

ERNEST E. UNDERWOOD, OF ROCHESTER, NEW YORK, ASSIGNOR TO EASTMAN KODAK COMPANY, OF ROCHESTER, NEW YORK, A CORPORATION OF NEW YORK.

FOCUSING MECHANISM FOR CAMERAS.

Application filed May 21, 1926. Serial No. 110,682.

This invention relates to photography and more particularly to the focusing cameras of the folding type. One object of my invention is to provide a mechanism by which the camera objective may be adjusted relative to the focal plane of the film. Another object is to provide a movable track upon which the lens carriage may move and a tensioning means to hold the track against the bed. Another object is to provide a track structure in which the guideways for the sliding track are concealed by means of a cover plate. Another object is to provide a combined cover plate and tensioning device for holding the track against the bed with the desired friction. Other objects will appear hereinafter from the following specification, the novel features being arranged in the claims at the end thereof.

It has been common practice to mount a movable camera track upon studs passing into the camera bed. This practice has certain disadvantages because the stock from which the camera track is made frequently varies in thickness and consequently, it is difficult to maintain a desired tension on the studs upon which the track slides. Obviously if the stock runs thick and with studs of a standard size, the track will bind; if the stock should run under the normal gauge the track may move too freely. My invention is particularly directed to overcome such manufacturing difficulties by providing a tensioning plate which will care for the usual stock variations and which will provide a uniform tension upon the track at all times.

Coming now to the drawings wherein like reference characters denote like parts throughout,

Fig. 1 is a side elevation of a typical folding camera constructed in accordance with and illustrating one form of my invention; Fig. 2 is a top plan view of the camera with the bed open, and with the camera carriage in a folded position;

Fig. 3 is a section on line 3—3 of Fig. 2; Fig. 4 is a plan view showing another embodiment of my invention with the track moving mechanism omitted;

Fig. 5 is a section on line 5—5 of Fig. 4;

Fig. 6 is a view of a camera bed equipped with a movable track constructed in accordance with another embodiment of my invention, parts being omitted for clearness; and

Fig. 7 is a section on line 7—7 of Fig. 6.

In the preferred embodiment of my invention shown in Figures 1 to 3 inclusive, I have shown a camera of the small folding type, comprising a body portion 1, to which is hinged a bed 2, which may be supported in an open position, as shown in Fig. 1 by means of the bed braces 3, which are pivoted at 4 to the bed. A bellows 5 is connected at one end to the camera body and at the other end 6 to a lens board 7, which supports the usual finder 8 and the camera shutter 9 in which the objective may be mounted. Only a portion 10 of the objective mounting is shown. The lens board 7 forms a part of the lens carriage 11, which is formed in two parts 12 and 13 hinged together at 14. Part 12 carries a hinged latch member 15 which may be operated by the handle 16, and which has a tail 17 adapted to engage in a notched latch 18 which, as best shown in Figure 2, is preferably attached to the track 20 by means of screws 19. The front section of the lens carriage 13 carries a knob 21 by which the lens carriage may be moved. A folding leg 22 is provided for supporting the camera on a flat surface. So far the described construction is of a well known type camera.

In order to focus the camera objective any desired track-moving mechanism may be employed. By way of illustration, I have shown in Figure 2 a fixed screw 23 supported at each end by the brackets 24. On this screw there is a knurled nut 25, having a groove 26 in it. This groove is adapted to receive one end 27 of a bracket which may be affixed to the track 20 by screws 28. Thus when the nut 25 is turned the track is moved on the camera bed to adjust the objective to various focal distances.

Coming now to my invention the track designated broadly as 20 may consist of a plate having cut-out areas 29. These areas may vary in size and shape, and are provided to lighten the weight of the camera and also to provide openings through which the studs 30 which support the track tensioning plate 31 may pass. In the embodiment shown in Fig. 2 the studs 30 may pass through the cut-out portions 29A.

Referring to Figure 3 it will be seen that the track 20 is provided with formed up edge portions 31, which are bent outwardly at 32 to form rails, which may be engaged by the lens carriage. I prefer to support

the track member 20 upon washers 33, which surround the studs 30, so as to space the track a short distance from bed 2. The plate 31 is of spring metal and it is held in a fixed position relative to the bed by means of the studs 30.

In the embodiment shown in the first three figures of the drawings the track 20 is guided by the studs 30 passing through the cutout portions 29^a, and is frictionally held against the bed by means of the spring plate 31. This frictional engagement insures smooth operation of the plate when it is moved by turning the nut 25.

In a second embodiment of my invention, illustrated in Figures 4 and 5, the camera track 20 is provided with cut-out portions 29 and the studs 30 pass up through these cut outs and are solely for attaching the tensioning plate 31 to the camera bed. In this form the edges 35 of plate 31 form a guideway which locates track 20, and which permits the track to slide under the influence of an actuating mechanism, such as that shown in Figure 2. Plate 31 not only guides track 20, but also frictionally holds it against the bed as in the first described embodiment.

In Figures 6 and 7 still another embodiment of my invention is shown. Here the track 20 is provided with the cut outs 29, the inner edges of which 36 may engage rollers 37 which may be supported by the studs 30. As shown in Figure 7, these studs pass up through the tensioning plate 31 and hold it in a fixed position relative to the bed 2. If desired the edges 36 may be formed downwardly at 38, so that a relatively small bearing surface may be produced, and the track 20 may be moved upon these flanges with a minimum contact with the camera bed.

In all of the above described embodiments of my invention there is a tensioning plate 31 provided to hold the track resiliently against the bed. This plate presents a smooth surface which covers up the cut-out portions of the camera track, and this plate may be suitably finished to improve the appearance of the camera.

Having thus described my invention, what I claim as new and desire to secure by Letters Patent is:

1. In a focusing device for cameras, the combination with a bed, of a track member movably mounted on the bed, and a tensioning plate supported by the bed and adapted to contact with the track member to resiliently press the latter against the bed.

2. In a focusing device for cameras, the

combination with a bed, of a track member movably mounted on the bed, and a tensioning plate, studs for attaching the tensioning plate to the bed, said studs passing through the track member whereby the track may be held under tension against and may be guided on the bed.

3. In a focusing device for cameras, the combination with a bed, of a track member including a plate having formed up lateral rails and cut-out areas lying between the rails, studs passing through said cut-out areas, and means for holding the track against the bed under tension comprising a spring member adapted to lie between the formed up rails, said spring member being attached to the bed by the studs.

4. In a focusing device for cameras, the combination with a bed, of a track member carried by the bed, a tensioning plate adapted to hold the track member under tension against the bed, and common means for guiding the track and holding the tensioning plate relative to the bed.

5. In a focusing device for cameras, the combination with a bed, of a track member carried by the bed, said track member being provided with a plurality of cut-out areas, studs carried by the bed passing through the cut-out areas, and a tensioning plate formed of spring metal mounted on the studs, said tensioning plate being adapted to press the edges of the track whereby the track may be frictionally pressed against the bed.

6. In a focusing device for cameras, the combination with a bed, of studs attached to the bed, a track movably mounted on the bed being guided by the studs, and a tensioning plate carried by the studs and frictionally engaging the track, whereby the track may be held against the bed.

7. In a focusing device for cameras, the combination with a bed, of a track movably mounted thereon, and a tensioning plate carried by the bed adapted to press the longitudinal edges of the track toward the bed.

8. In a focusing device for cameras, the combination with a bed, of a track carried by the bed, said track including a plate with formed up rails along the lateral edges of the plate, and resilient means adapted to press the track against the bed, said means contacting with the track along the base of the rails.

Signed at Rochester, New York, this 18th day of May, 1926.

ERNEST E. UNDERWOOD.
